Primary Examiner — Patricia Palasik*(74) Attorney, Agent, or Firm* — Philip W. Townsend, III**CLAIM**

The ornamental design for a drill bit with a pointed cutting element, as shown and described.

DESCRIPTION

FIG. 1 is a bottom perspective view of a drill bit with a pointed cutting element.

FIG. 2 is a side view of a drill bit with a pointed cutting element; and,

FIG. 3 is a perspective view of a drill bit with a pointed cutting element.

The broken lines in the drawings depict unclaimed environmental subject matter.

1 Claim, 2 Drawing Sheets## Related U.S. Application Data

filed on Nov. 16, 2009, which is a continuation-in-part of application No. 11/766,975, filed on Jun. 22, 2007, now Pat. No. 8,122,980, application No. 29/376,990, which is a continuation-in-part of application No. 11/673,634, filed on Feb. 12, 2007, now Pat. No. 8,109,349.
